UNITED STATES PATENT OFFICE

JAMES A. C. KRIPS, OF HADDONFIELD, NEW JERSEY, ASSIGNOR TO I-T-E CIRCUIT BREAKER COMPANY, OF PHILADELPHIA, PENNSYLVANIA, A CORPORATION OF NEW JERSEY

SWITCH APPARATUS

Application filed March 17, 1930. Serial No. 436,830.

My invention relates to improvements in switching mechanism comprising separable component units, for controlling electric power, lighting and other circuits.

5 An object of my invention is to provide in switching mechanism of the character referred to improved means whereby one unit is entirely supported or hung from an associated or complementary unit during and 10 after separation of the units which are maintained in alignment with respect to each other for subsequent movement back into operative register with each other.

In accordance with my invention, a switch 15 unit or structure is entirely supported by pantograph structure upon an associated unit from and back to which it is movable in a straight line to separate and reengage its contacts from and with fixed contacts permanently connected to buses or supply lines.

Further in accordance with my invention, means are provided for enabling the operator to effect separation of the movable from the stationary units without unusual effort, al- 25 though relatively great force be required as in the case where the coacting switch contacts engage or wipe upon each other with considerable friction.

My invention resides in apparatus of the 30 character hereinafter described and claimed.

For the purpose of illustrating my invention, one embodiment thereof is shown in the drawings, in which:

Fig. 1 is a front elevational view of switch- 35 ing mechanism embodying my invention;

Fig. 2 is a plan view, partly in section, on line 2—2 in Fig. 1;

Fig. 3 is a fragmentary sectional view on line 3—3 in Fig. 1;

40 Fig. 4 is a sectional view on line 4—4 in Fig. 3;

Fig. 5 is an enlarged detail sectional view taken from Fig. 3; and

Fig. 6 is a sectional view on line 6—6 in 45 Fig. 2.

The switching mechanism comprises the complementary separable structures or units designated generally by reference numerals 10 and 11.

50 The fixed unit 11 is secured to a switch-

board, wall, or any suitable support. It is provided with a set of contacts 12, 13 and 14 connected permanently to the respective bus bars 15, 16 and 17, and mounted on an insulating base 18; below them on base 18 is mounted a second set of contacts 19a, 19b and 19c, each provided with a suitable terminal 20 for connection of feeder lines.

55 The movable switch unit 10 comprises the casing 21 in which are disposed three switches, specifically a three pole automatic circuit breaker whose switch components for the three poles are indicated respectively by the broken lines 22, 23 and 24, operated and controlled by levers 25 and 26.

60 Contacts 27 and 28 in the unit 10 are complementary respectively to the contacts 12 and 19a which are received by the associated contacts upon movement of switch structure 10 to the right into operative relation with respect to the fixed terminal or bus structure 11, at which time the usual fixed and movable switch contacts of breaker 22 are connected respectively through contacts 27 and 28 to contacts 12 and 19a. In like manner, upper 65 and lower contacts 29 receive the respective contacts 13 and 19b to connect breaker 23 therewith, while contacts 30 receive the respective contacts 14 and 19c to connect breaker 24 thereto.

70 Each of the contacts 27, 28, 29, 30 is provided with flexible connections thereto, not shown. These contacts are supported by springs 31 which cause the contacts to exert a relatively strong gripping action upon their coacting contacts when operatively engaged therewith. This gripping action is effective 75 to hold switch structure 10 against free movement out of operative relation with respect to the fixed structure 11. The gripping action is so great that in switch gear of large capacity it is difficult to separate unit 10 from unit 11.

80 In accordance with my invention, means are provided to enable an operator readily to separate the two structures, and to this end unit 10 is connected to the fixed unit 11 by pantograph structures, designated generally 85 by reference numerals 32 and 33, which operate to support the switch structure 10 for 90 100

movement into and out of operative relation with respect to the fixed structure, and entirely to support it upon the fixed structure during such movement.

5 The pantograph structure 32 comprises the uprightly disposed links 34 and 35 pivotally connected intermediate their ends by the pin 36 and spaced by suitable plates 37 secured to the links. The upper end of link 35 is pivotally mounted on the end of a rod 38 supported at its opposite ends by suitable lugs or flanges 39 which may be welded or otherwise secured to the vertical angle members 40 forming part of structure 11. The lower end of link 35 is provided with a pin 41 received by and having a sliding fit in a vertical slot 42 in a suitable plate 43 welded to the inside of flanged plate 65.

20 The upper end of link 34 is pivotally mounted on the end of a rod 44 supported at its ends in suitable angle brackets 45, as more clearly shown in Fig. 2.

25 The pantograph structure 33 is identical with pantograph structure 32 just described, and is connected to the complementary units 10 and 11 in the same way.

30 The pantographs 32 and 33 operate to connect switch structure 10 for straight-line movement into and out of operative or connected relation with respect to the fixed structure 11, and entirely to support the unit 10 from the fixed unit 11 during such movement, as shown in Figs. 1 and 2. The pin 36, as shown in Fig. 1, is preferably not at the center of links 34 and 35 but is nearer the ends of the links connected to plate or panel 43 so that when the movable unit is in circuit-controlling position with the rear flanges of panel 43 against the angle members 40 of the fixed unit, the links 34 and 35 overlie one another with little or no angle between them.

35 To withdraw switch unit 10 from unit 11 against the powerful opposing gripping action at the contacts, force-multiplying means of any suitable type are provided. In the example illustrated, screw-and-nut mechanism is provided, comprising a flat triangular plate 46, whose plane is parallel to the path of movement of unit 10, secured at its base portion to an angle member 47 carried by structure 10, and provided at its apex with a nut 48. A screw 49 engages nut 48, and is supported for rotation in suitable lugs or bearing blocks 50 and 51 on structure 11.

40 A suitable thrust bearing 52, disposed on the reduced end portion 53 of screw 49, and disposed between the shoulder 54 and a bushing 55, operates to hold the screw against appreciable axial movement, while permitting free rotation thereof. A gear 56 fixed on screw 49 meshes with a smaller gear 57 fixed on the shaft 58 having a reduced end portion 59 journalled in a bearing plate 60 and on which is fixed a collar 61. Shaft 58 is parallel to screw 49, as shown in Figs. 2 and 3, and ex-

tends loosely through suitable bearing blocks or lugs 62 and 63 associated respectively with the structures 11 and 10.

45 By a wrench applied to its square end 64 shaft 58 is rotated to cause rotation of screw 49 with consequent movement of unit 10 with respect to unit 11.

50 From the foregoing it will be seen that the screw-and-nut mechanism provides means whereby the switch structure 10 may be readily separated from fixed structure 11 to disengage their contacts, as shown in Figs. 1 and 2, and moved without difficulty back into operative position with respect to the fixed structure.

55 During such movement of the switch structure, plate 46 operates as a brace to minimize lateral or torsional deflection of the pantographs, and as a guide to maintain proper alignment of units 10 and 11, so that the contacts of one are always in position for proper registration with the contacts of the other.

60 What I claim is:

1. The combination with a fixed unit comprising contacts, of a movable unit comprising switch mechanism and contacts connected therewith, link structure disposed in a vertical plane capable of wholly supporting said movable unit upon said fixed unit for horizontal straight-line movement of said movable unit to effect separation of the contacts thereof from those of said fixed unit, and means coacting with said units for preventing torsional deflection of said link structure about a vertical axis during said movement of said movable unit.

2. The combination with a fixed unit comprising contacts, of a movable unit comprising switch mechanism and contacts connected therewith, link structure disposed in a vertical plane capable of wholly supporting said movable unit upon said fixed unit for horizontal straight-line movement of said movable unit to effect separation of the contacts thereof from those of said fixed unit, and force-multiplying means for effecting movement of said movable unit with respect to said fixed unit connecting said unit for all positions of said movable unit.

3. The combination with a fixed unit comprising contacts, of a movable unit comprising switch mechanism and contacts connected therewith, link structure disposed in a vertical plane capable of wholly supporting said movable unit upon said fixed unit for horizontal straight-line movement of said movable unit to effect separation of the contacts thereof from those of said fixed unit, and force-multiplying means for effecting movement of said movable unit with respect to said fixed unit, said means comprising coacting members attached respectively to said fixed and movable units and so disposed as to prevent torsional deflection of said link structure about a vertical axis.

4. The combination with a fixed unit comprising contacts, of a movable unit comprising a panel, contacts extending from one side of said panel for engagement with said contacts of said fixed unit, switch mechanism carried by said panel having contact structure connected to said second contacts, said switch mechanism operable from the other side of said panel, and link structure supporting said movable unit upon said fixed unit, maintaining said second contacts in substantially the same horizontal plane for all positions of said movable member, and effecting separation and engagement of said contacts upon movement of said movable unit away from and toward said fixed unit respectively. 10 75
5. The combination with a fixed unit comprising contacts, of a movable unit comprising a panel, a circuit breaker mounted on the front of said panel, contacts connected to said circuit breaker and extending from the rear of said panel for engagement with said first contacts, and pantograph structure supporting said movable unit comprising links pivoted to each other, having their upper ends pivoted at fixed points on said units, and their lower ends slidably pivoted on said units. 20 85
6. The combination with a fixed unit comprising contacts, of a movable unit comprising a panel, a circuit-breaker mounted on the front of said panel, contacts connected to said circuit-breaker and extending from the rear of said panel for engagement with said first contacts, and pantograph structure supporting said movable unit from said fixed unit comprising links pivoted to each other at points unequally spaced from their ends to 30 permit them to assume overlying position for the limit of travel of said movable unit effecting engagement of said contacts. 90 95
7. The combination with a fixed unit comprising contacts, of a movable unit comprising switch mechanism and contacts connected thereto, link structure supporting said movable unit upon said fixed unit for horizontal straight-line movement of said movable unit to effect separation of said contacts of said 40 units, and means for effecting movement of said movable unit and for holding said unit against accidental displacement in intermediate position to which it is moved. 100 105
8. The combination with a fixed unit comprising contacts, of a movable unit comprising switch mechanism and contacts connected thereto, link structure supporting said fixed unit for horizontal movement of said movable unit to effect separation of said contacts of said 50 units, and means for preventing torsional movement of said movable unit about a vertical axis comprising mechanism including members attached to the fixed and movable units. 110 115
9. The combination with a fixed unit comprising contacts, of a movable unit comprising switch mechanism and contacts connected thereto, link structure supporting said movable unit upon said fixed unit for horizontal straight-line movement of said movable unit in effecting separation of said contacts of said units, and means for effecting movement of said movable unit comprising structure supported by said fixed unit and operated from the front of said movable unit. 10 75
10. The combination with a fixed unit comprising a compartment and fixed contacts therein, of a movable unit comprising a panel, a circuit breaker on the front thereof, contacts extending from the rear of said panel for engagement with said first contacts within said compartment, pantograph structure for supporting said movable unit for substantially horizontal movement comprising links having their upper ends pivoted at fixed points of said panel and fixed unit and their lower ends slidably engaging said panel and said fixed unit, and means for effecting movement of said movable unit comprising structure supported by said fixed unit and operated from the front of said panel. 80 85 90
11. In a switch structure containing a compartment, a circuit breaker on the front of movable panel supported from said structure, means furnished whereby substantially horizontal straight line parallel motion perpendicular to said panel is effected to actuate dis-connecting switch mechanism behind said movable panel and sealed from arc communication with said circuit breaker, said means comprising vertical pantograph linkage supporting said panel from said structure and guiding mechanism whereby angular and lateral motion is prevented, and means for holding panel in a plurality of positions against accidental displacement. 95 100 105
12. An electrical switch structure containing fixed contacts, a movable panel borne by link mechanism from said structure and supporting on the back complementary contacts engageable with said fixed contacts, means for controlling said contacts by permitting restricted motion of panel substantially solely in line normal to its surface, a circuit breaker on the front of said panel and connected with said complementary contacts, said circuit breaker and said engageable contacts controllable from front of said structure, and means for preventing arc communication between circuit breaker and said contacts. 110 115 120
13. In an electrical switch structure, a fixed panel with contacts and a movable panel parallel to and facing said fixed panel and supported from said structure by links, contacts on movable panel engageable with said contacts on said fixed panel, means for effecting limited movement of said movable panel toward and away from said fixed panel and for holding it at a plurality of positions 125 130

against accidental displacement, and means for preventing vertical or horizontal angular motion between panels, and for restricting the direction of motion to that substantially normal to the surface of panel.

14. The combination with a fixed unit comprising contacts, of a movable unit comprising switch mechanism and contacts connected thereto, link structure supporting said movable unit upon said fixed unit for horizontal straight-line movement of said movable unit in effecting separation of said contacts of said units, and means for holding said movable unit against accidental displacement in any position to which it may be moved.

15. The combination with a fixed unit comprising contacts, of a movable unit comprising switch mechanism and contacts connected thereto, link structure supporting said movable unit upon said fixed unit for horizontal straight-line movement of said movable unit in effecting separation of said contacts of said units, and means for effecting movement of said movable unit comprising screw-threaded structure supported by said fixed unit and operable from the front of said movable unit, said means adapted to hold said movable unit against accidental displacement in any position to which it may be moved.

16. The combination with a fixed unit comprising contacts, of a movable unit comprising switch mechanism and contacts connected thereto, link structure supporting said movable unit upon said fixed unit for horizontal straight-line movement of said movable unit in effecting separation of said contacts of said units, and means for effecting movement of said movable unit comprising a plate member whose plane is parallel to the path of movement of said movable unit, said plate member secured at one end to said movable unit and having screw-threaded means secured to its opposite end and supported by said fixed unit.

17. The combination with a fixed unit comprising contacts, of a movable unit comprising a panel, a circuit-breaker mounted on the front of said panel, contacts connected to said circuit-breaker and extending from the rear of said panel for engagement with said first contacts, pantograph structure supporting said movable unit from said fixed unit comprising links pivoted to each other at points unequally spaced from their ends to permit them to assume overlying position for the limit of travel of said movable unit effecting engagement of said contacts, and means including screw-threaded structure operable from the front of said movable unit, for effecting movement of said unit and for holding the unit against accidental displacement in any position to which it may be moved.

18. The combination with a fixed unit comprising contacts, of a movable unit comprising switch mechanism and contacts connected

thereto, link structure supporting said movable unit upon said fixed unit for horizontal straight-line movement of said movable unit in effecting separation of said contacts of said units, means for effecting movement of said movable unit comprising a plate member whose plane is parallel to the path of movement of said movable unit, said plate member secured at one end to said movable unit and having screw-threaded means secured to its opposite end and supported by said fixed unit, and means comprising a member extending to the front of said movable unit for actuating said screw-threaded means.

19. The combination with a fixed unit comprising contacts, of a movable unit comprising switch mechanism and contacts connected thereto, link structure supporting said movable unit upon said fixed unit for horizontal straight-line movement of said movable unit in effecting separation of said contacts of said units, means for effecting movement of said movable unit comprising a flat triangular plate whose plane is parallel to the path of movement of said movable unit, said plate secured at its base portion to said movable unit, and provided at its apex with screw-threaded means supported by said fixed unit, and means extending to the front of said movable unit for actuating said screw-threaded means.

JAMES A. C. KRIPS.
